UNITED STATES PATENT OFFICE

112,532

DESIGN FOR A GLASS BOTTLE

John H. Meier, Jr., Pittsburgh, Pa., assignor to
J. T. & A. Hamilton Company, a corporation of
Pennsylvania

Application June 3, 1938, Serial No. 77,547

Term of patent 14 years

To all whom it may concern:

Be it known that I, John H. Meier, Jr., a citizen of the United States, residing at Pittsburgh, in the county of Allegheny and State of Pennsylvania, have invented a new, original, and ornamental Design for a Glass Bottle, of which the following is a specification, reference being had to the accompanying drawing, forming part thereof.

In the drawing Fig. I is a view in side elevation of a bottle showing my new design, and Fig. II is a view of the bottle in plan from above.

The characteristic features of my design reside in a bottle of cylindrical form, having a neck that is radially enlarged in two axially aligned circum-

ferential zones, the two circumferential enlargements being curved to blend with the body of the bottle below and the capital above, and merging in a constriction between the said zones. The major diameter of the two enlargements is greater than the diameter of the capital and less than the diameter of the body of the bottle, and the diameter in the region of constriction between said enlargements is greater than the diameter in which the lower enlargement merges with said body of the bottle.

I claim:

The ornamental design for a glass bottle, substantially as shown and described.

JOHN H. MEIER, JR.
